UNITED STATES PATENT OFFICE.

JOHN J. MURPHY, OF NORWICH, CONNECTICUT, ASSIGNOR OF ONE-HALF TO
RUTHERFORD C. PLAUT, OF NORWICH, CONNECTICUT.

POLICE-NIPPERS.

1,147,423.

Specification of Letters Patent. Patented July 20, 1915.

Application filed March 29, 1915. Serial No. 17,747.

To all whom it may concern:

Be it known that I, JOHN J. MURPHY, a citizen of the United States, residing at Norwich, in the county of New London, in the State of Connecticut, have invented a certain new and useful Improvement in Police-Nippers, of which the following is a specification, reference being had to the accompanying drawings.

10 This invention relates to police nippers or so called "leaders", of the type that are clasped upon the wrists of criminals and other offenders, and my object is to provide a particularly convenient, and reasonably 15 cheap, form of nippers that may be instantly clasped in locking position on the wrist of an offender by a single movement of the officer; the construction being such that the device may be operated with one hand only, 20 either to lock the nippers on the wrist or to release them therefrom.

My said invention is clearly illustrated in the annexed drawings, in which—

Figure 1 is a plan view of a pair of nippers embodying my present improvements, showing said nippers closed; Fig. 2 is a similar view showing the nippers opened, and Fig. 3 is an edge view of the same. Fig. 4 is a detail view of the main or basic frame member, upon which the adjustable, locking, members of the nippers are mounted, and Fig. 5 is a detached view of the tubular member 15 which is adapted to slide longitudinally on the said basic member, 35 and said Fig. 5 also illustrates two spreader arms which, in the assembled device, are hinged to the tubular member 15, as I will explain more particularly later. Fig. 6 is a side view of the member 15. In Fig. 7 I 40 have shown, detached, by side and edge views, one of the locking jaws of the nippers. Fig. 8 is a relatively enlarged, side, view of a spring-controlled latch by means of which the nippers are locked in their 45 closed position and, in the Fig. 9, I have illustrated particularly a simple form of spring which will operate automatically to open the jaws of the nippers when the said latch is released.

50 Referring to these drawings, the numeral 10 indicates what I term the basic member of my improved nippers inasmuch as the various adjustable, or movable, elements are mounted on said basic member. Said member comprises a rod portion that is pro-

vided, as here shown, with notches 11 and has at one end a T-shaped handle 12; the other end of the rod being formed with oppositely extending arms 13—14 to whose free end portions are hinged the jaws 60 13^a and 14^a respectively.

Mounted to slide longitudinally on the basic rod 10 is a tubular member 15 which has at one end a T-shaped handle 15^a which lies in the same plane as the handle 12 above 65 described; the other end portion of the said tubular member having hinged thereto, by a rivet or screw 15^b oppositely extending arms 16 and 17 whose otherwise free ends are hinged, respectively, to the described 70 jaws 13^a and 14^a and serve to open and close the said jaws when the member 15 is slid on the basic rod 10.

In order to lock the nipper jaws in their closed positions I have provided a latch 18, 75 of lever form, which is fulcrumed on a rivet 19, one end of said latch being adapted to engage, and interlock with, the notches 11, already referred to; the latch being held yieldingly in engagement with the notches 80 by a spring 20, as is best seen in Fig. 8 of the drawings.

The operation of my described nippers is as follows, assuming that they are open as seen in Fig. 2 of the drawings:—The handle 85 12 is grasped and the jaws 13^a—14^a are slipped upon opposite sides of the wrist of the offender and the, preferably enlarged, head 15^c of the slidable member 15 is forced quickly against the wrist, which checks the 90 advance movement of the member 15 but allows the basic rod 10 to be slid forward in member 15 thus causing the bars 16—17 to draw the jaws 13^a and 14^a together, as seen in Fig. 1 and thus to encircle the of- 95 fender's wrist: the ends of the jaws being offset from each other, as will be understood by reference to the Figs. 1 and 3 of the drawings. As the rod 10 slides forward into the tubular member 15 the latch 18 100 snaps automatically, and successively, into the notches 11 and thus effectively locks the jaws against accidental separation. If it is desired to close the jaws onto a wrist without pressing the head 15^c against the offend- 105 er's wrist as above described, it may be readily accomplished by grasping both of the handles (12 and 15^a) and, by a closing movement of the fingers and thumb, slide the handle 15^a toward the handle 12; the 110

latch 18 meanwhile engaging the notches 11 as first above described.

My described device is quick in its closing movement, it is strong in its parts, it 5 may be cheaply manufactured, and it is extraordinarily convenient in its operation, for the reason that it can be operated by one hand.

Having thus described my invention I 10 claim as new and wish to secure by Letters Patent:

1. In police nippers, in combination, a notched and handled basic rod having oppositely extending fixed arms, jaws hinged to 15 said fixed arms, a member slidably mounted on said rod, and spreader arms connecting said slid- able member with said jaws.

2. In police nippers, in combination, a handled basic rod having oppositely ex- 20 tending fixed arms, jaws hinged to said fixed arms, a member slidably mounted on said rod, spreader arms connecting said slid-

able member with the said jaws, and means for yieldingly latching the said slidable member to the said rod.

3. In police nippers, in combination, a notched and handled basic rod having oppositely extending fixed arms, jaws hinged to said rod, a member slidably mounted on said rod, and spreader arms connecting said slid- 25 able member with said jaws; the said slid- able member being formed with an enlarged head.

4. In police nippers, in combination, a notched and handled basic rod, jaws hinged to said rod, a member slidably mounted on said rod, and arms connecting the said slid- 30 able member and jaws, and coöperating with said jaws to form the wrist clasp.

JOHN J. MURPHY.
